[57] **CLAIM**

The ornamental design for a front element for an electrical control and signaling unit, as shown and described.

DESCRIPTION

FIG. 1 is a top, front, and left side perspective view of a front element for an electrical control and signaling unit showing the first embodiment of my new design, the rear and right sides being identical in appearance; and,

FIG. 2 is a top, front, and left side perspective view of a front element for an electrical control and signaling unit showing the second embodiment of my new design, the rear and right sides being identical in appearance.

The broken-line showing of the electrical control and signaling unit in the views is for illustrative purposes only and forms no part of the claimed design.
